ELECTRON MULTIPLIER

Hans Wolfgang Langenwalter, Berlin-Zehlendorf,
Germany, assignor to the firm of Fernseh
Aktiengesellschaft, Zehlendorf, Germany

Application February 22, 1938, Serial No. 191,851
In Germany February 20, 1937

4 Claims. (Cl. 250—175)

Electron multipliers are known in which the primary current is multiplied by means of several electron-permeable secondary emitting electrodes arranged in consecutive order. These secondary emitting electrodes may have the form of mesh-works, sieves or foils.

In such arrangements the danger often arises that lateral electrical fields deflect the electrons from the desired paths, and thereby withdraw them from further multiplication. This may be the case particularly if electrodes are disposed in the proximity of the multiplying arrangement, which electrodes have a positive potential in respect to at least several of the secondary emitting electrodes. For instance, in Farnsworth dissector tubes, it is preferable for circuit reasons to dispose the secondary emitting electrodes inside of a screening cylinder, the potential of which is positive in respect to all or at least to several secondary emitting electrodes.

In order to avoid or decrease the influence of lateral accelerating fields, it is the object of the invention to provide several or all secondary emitting electrodes with a curvature in the direction towards the primary source of electrons in the multiplying arrangement. An accelerating field is then formed between two secondary emitting electrodes, which field possesses a lateral component in the direction toward the axis of the system and thereby exerts a concentrating effect upon the electron stream. Simultaneously, the shape of the secondary emitting electrodes has a certain screening effect upon the interior of the multiplier.

The drawing shows an embodiment of the invention. The entire arrangement is disposed in a vacuum receptacle 11, representative of a Farnsworth disector tube. The cylindrical screen 1, provided with a minute aperture 12, surrounds an oblique plate 13 having a secondarily emissive surface, the secondary emitting grids 2 to 8, an electron-permeable anode 9 and a solid secondary emitting electrode 10. Electrons emitted from the photoelectric cathode (not shown) of the Farnsworth disector tube enter the screen 1 through the aperture 12 and impact the plate 13, whereby they produce secondary electrons. For the explanation of the invention, the plate 13 will be considered as the source of primary electrons for the remainder of the multiplier structure inasmuch as the type of source of the primary electrons is immaterial to the invention. The majority of the electrons travels through the anode 9 after multiplication at the grids 2 to 8, impacts the plate 10 and effects

another multiplication at this plate. In this manner, higher efficiency is obtained than would be the case if plate 10 were used as collecting anode. The screening cylinder 1 may be held at a potential positive in respect to all secondary emitting electrodes. It may be conductively connected with a screen on the outside of the tube which leads to the input of the following amplifier. The curvature of the secondary emitting electrodes is, as may be seen from the drawing, adjusted in accordance with the potential difference between the respective secondary emitting electrodes and the surrounding cylinder, i. e., the curvature is increased with increasing potential difference. Plate 10 has a concave curvature in respect to the anode because a reversal of the electron paths takes place at this plate.

While, in this case, the cylinder completely surrounds the secondary emitting electrodes, and these are given spherical curvatures, the invention can obviously also be applied in cases where the electrodes, whose fields reach into the multiplier arrangement, are, for instance, located only on two opposite sides of the multiplying arrangement. In such a case, it may suffice to curve the secondary emitting electrodes in one direction only, i. e., cylindrically.

It may be understood that the invention can also be applied to multipliers which possess one or several solid secondary emitting electrodes in front or in back of a series of electron-permeable electrodes.

I claim:

1. An electron multiplier device comprising a source of electrons, a plurality of successive secondary emissive electrodes, a collector electrode positioned between two of said secondary emissive electrodes, said secondary emissive electrodes being of concave shape as viewed from said collector electrode, the decrease in the radii of curvature of said electrodes progressing more rapidly than the increase in spacing of said secondarily emissive electrodes from said collector.

2. An electron multiplier device comprising a source of electrons, a plurality of successive secondary emissive electrodes, a collector electrode positioned between the last and the preceding of said secondary emissive electrodes, those of said secondary emissive electrodes on one side of said collector electrode being of concave shape as viewed from said source of electrons and the last of said electrodes on the other side of said collector electrode being convex as viewed from said source of electrons.

3. An electron multiplier device having a source of electrons, a collector electrode and a plurality of secondary emissive electrodes intermediate said source of electrons and said collector electrode, said secondary emissive electrodes being of convex shape as viewed from said source of electrons with the convexity of each succeeding electrode varying with respect to the preceding electrode.
10. 4. An electron multiplier device comprising a source of electrons, a plurality of successive

secondary emissive electrodes, a collector electrode positioned between two of said secondary emissive electrodes, those of said secondary emissive electrodes on one side of said collector electrode being of concave shape as viewed from said collector electrode, with the radius of curvature of said secondary emissive electrodes decreasing with increasing distance from said collector electrode.
